UNITED STATES PATENT OFFICE.

NORA BLATCH DE FOREST, OF NEW YORK, N. Y.

DESIGN FOR AN ARTICLE OF MANUFACTURE.

45,799.

Specification for Design.

Patented May 19, 1914.

Application filed April 28, 1913. Serial No. 764,286. Term of patent 14 years.

To all whom it may concern:

Be it known that I, NORA BLATCH DE FOREST, a citizen of the United States, and a resident of the borough of Manhattan, city, county, and State of New York, have invented a new, original, and ornamental Design for an Article of Manufacture, of which the following is a specification, reference being had to the accompanying drawing, forming

part thereof and illustrating my new design to be applied to an article of manufacture.

I claim:

The ornamental design for an article of manufacture as shown.

NORA BLATCH DE FOREST.

Witnesses:

M. CARL LOOMIS,
SIGMUND RUBIN.
